UNITED STATES PATENT OFFICE.

CLAUDE W. WENTZELL, OF HARPER'S FERRY, WEST VIRGINIA, ASSIGNOR
OF ONE-HALF TO WILL O. RAU, OF SAME PLACE.

RAILROAD-SWITCH.

SPECIFICATION forming part of Letters Patent No. 544,705, dated August 20, 1895.

Application filed March 28, 1895. Serial No. 543,586. (No model.)

To all whom it may concern:

Be it known that I, CLAUDE W. WENTZELL, a resident of Harper's Ferry, in the county of Jefferson and State of West Virginia, have invented certain new and useful Improvements in Railroad-Switches; and I do hereby declare the following to be a full, clear, and exact description of the invention, such as will enable others skilled in the art to which it appertains to make and use the same.

My invention relates to an improvement in railroad-switches, the object of the invention being to produce simple and efficient means whereby to insure the automatic closing of a switch when a train shall have passed the same, whether the train be running onto or off of a siding.

A further object is to so construct a railroad-switch and devices connected therewith that after the switch shall have been manually set for the siding it will be automatically released by a car passing thereon, but maintained open by the weight of the train until the latter shall have passed wholly onto or off of the siding, and then release the entire switch mechanism and permit the switch to automatically close and lock.

A further object is to produce an automatically-closing railroad-switch which shall be simple in construction, sure and easy in operation, and effectual in all respects in the performance of its functions.

With these objects in view the invention consists in certain novel features of construction and combinations and arrangements of parts, as hereinafter set forth, and pointed out in the claims.

In the accompanying drawings, Figure 1 is a plan view illustrating my invention. Figs. 2 and 3 are side views illustrating a portion of the switch-operating devices. Figs. 4 and 5 are detail views.

A A' represent the main rails of a railroad-track; B B', the rails of a siding, the rail B' constituting a continuation of the main rail A, and C C' represent the pivoted switch-rails. A series of brackets *a* is disposed parallel with the rails A B in line with the edge of the outer flange *a'* thereof, each bracket having a portion *a''* extending under the rails and

secured to the flanges thereof by means of suitable bolts. The brackets *a* are tied together by means of bars or straps *a''*, one end of each strap being secured to the web of the rail. Spacing-blocks *a''* are disposed parallel with the outer face of the web of the rail A, B and made of a thickness about equal to one-half the diameter of the tread of the rail, so as to cause the upper edge of a longitudinally-movable bar or rail D, located between said blocks and brackets, to be normally disposed close to and flush with the tread of the rail. The movable bar or rail D is of a length somewhat greater than the distance between two trucks of a railroad-car, so that when a train is passing over it a wheel will always be upon said bar or rail until the entire train shall have passed over the switch. The movable bar is made with a series of curved slots *b*, preferably corresponding in number with that of the brackets *a* and spacing-blocks *a''*. Through each bracket *a*, spacing-block *a''*, slot *b*, and the web of the rail bolts *b'* are passed, the intermediate portions of said bolts being made of greater diameter than the ends to form shoulders *b''*, which bear against the brackets *a* and blocks *a''* and keep them properly spaced apart, so as to prevent the movable bar or rail D from binding.

By connecting the rail or bar D with the rails A B, as above described, it will be seen that when said bar is moved longitudinally it will be caused also to move upwardly slightly above the tread of the rail, for a purpose hereinafter explained.

The switch-rails are pivotally connected with a movable switch bar or rod *c*, located under the rails and projecting laterally beyond the rail B. To the end of the rod or bar *c* one end of an arm *c'* is pivotally connected, and the other end of said arm is pivotally connected to an arm *d* of a lever *d'*. The lever *d'* is pivotally supported between its ends in a suitable bracket *d''*, and to the arm *d''* of said lever one end of a connecting-rod *e* is pivoted, the other end of said connecting-rod being pivotally attached to ears *e'*, projecting from the movable bar or rail D. To the free end of the arm *d''* of the lever *d'* one end of a rod *f* is pivotally connected, 100

the other end of the rod f being pivotally connected to an arm g , depending from a shaft h , and the latter is mounted in a suitable stand h' . To the other end of the shaft h an operating-lever E is secured, by manipulating which the pivoted switch-rails will be shifted and the movable bar or rail D moved longitudinally.

- The stand h' is made with an enlargement 10 h^2 , on which a shaft i is mounted in rear of the shaft h , and to one end of said shaft i an operating-lever E' is secured, so as to be directly in line with the lever E , and so that when the levers are in their normal positions 15 the lever E' will be immediately over the lever E . The lever E' is provided with an arm i' , adapted to enter and engage a lock i^2 , whereby to retain said lever E' normally locked, and said lever E' being directly over 20 the lever E the latter will be also locked. An arm j is secured to the shaft i and depends therefrom, the lower end of said arm being bifurcated for the reception of a bar k , having a slot k' , and through the bifurcated end 25 of the arm j and the slot k' a pin k^2 passes. One end of the slotted bar k is pivoted to the lower end of the arm g , which depends from the shaft h . A stand l is located in rear of the stand h' , and has a horizontal shaft l' 30 mounted thereon. To one end of the shaft l' a weighted arm m is secured, and to the other end of said shaft a depending arm n is fixed. A connecting-rod o is pivoted at one end to the depending arm n , and at the other 35 end said connecting-rod is pivotally attached to the depending arm j , at a point between the ends of the latter. The lower end of the depending arm n projects through a slot p in a plate p' , the latter being secured to the base 40 p^2 , on which the stands are mounted. A latch-bar q , pivotally connected to the plate p' , projects within the slot p and is adapted to be engaged by the depending arm n , the outer end of said latch-bar being pivotally connected 45 to a rod q' , adapted to move freely through perforated brackets q^2 , secured to the base p^2 , and on said rod, between the brackets q^2 , a spring r is located. The bifurcated end 50 of a longitudinally-movable bar or rod s receives the latch-bar at a point between the ends of the latter, and is pivotally connected to it by a pin r' , said pin passing through elongated slots r^2 in said bifurcated end of the rod or bar s . The longitudinally-movable 55 rod or bar s extends under the rails between two ties, and at its free end is provided with an upwardly and forwardly projecting arm s' , which is pivotally connected between ears s^2 , projecting from a curved spring-bar t . The 60 bar t is secured at one end to suitable brackets u , fixed to the ties, and between its ends is normally disposed in close proximity to the tread of the siding-rail B' at a point near the pivoted switch-rail C' . The flanges of the 65 wheels of a train passing over the rail B' will enter between the tread of the rail and the

spring-bar t , and force said spring-bar laterally. The spring-bar is made with a hole v for the passage of a small rod v' , secured to suitable brackets, whereby to guide the movements of said bar. 70

Let it be assumed that it is desired that the train shall run from the main track onto the siding. The switchman will first unlock the levers E E' . He will then raise the lever E' , 75 which operation will cause the oscillation of the shaft l' through the medium of the intermediate connections above described. As the shaft l' is operated, the weighted arm m will be raised and the depending arm n will be 80 moved, so as to be engaged by the latch-bar q , which latter will serve to retain the parts in the positions to which they have been moved. When the lever E' shall have been raised, the pin k^2 at the lower end of the arm j will have moved to the end of the slot k' in the bar k nearest the pivoted end of said bar. The switch-operating lever E will now be raised, so as to shift the pivoted switch-rails C C' and throw the long bar D from one end 85 of its movement to the other, as above explained. When the lever E is thus raised, the slotted bar k will be moved, so as to cause the pin k^2 to become disposed near the opposite end of the slot k' in said bar. The switch 90 and its operating mechanism are now set, and the train moves on the siding. The wheels of the train running on the rail A B will maintain the long bar D in the position to which it has been set—viz, flush with the tread 95 of the rail. The first wheel of the train which reaches the spring-bar t will move said bar, as above described, which movement will be transmitted to the latch-bar q through the medium of the bar s to cause the depending 100 arm n to be released therefrom. The shaft l' will then be permitted to turn slightly until the pin k^2 reaches the end of the slot k' in the bar k . The switch-operating mechanism will now have been released, and the various parts 105 thereof will be connected together, the weighted arm m tending to cause all the parts to return to their normal positions to close the switch, but will be prevented by the weight of the train on the long movable bar D , which, 110 in order to move longitudinally to its normal position, must first move upwardly slightly above the tread of the rail; but this latter movement will of course be prevented by the wheel running over it, there being always at 115 least one wheel on said bar as long as the train is passing. As soon as the last wheel of the train shall have passed over the bar D , no further resistance will be offered to the action of the weighted arm n , and the latter 120 will therefore drop, causing the various parts of the mechanism to assume their normal positions and the switch to be closed automatically. When the operating-levers E E' drop, 125 the arm i' on the lever E' will enter the lock i^2 , and said levers will thus become automatically locked, as above explained, so that the 130

switch cannot be again thrown until said levers shall have been unlocked by the use of the proper key.

It is evident that the mechanism will be 5 operated in the same manner when a train is to pass from the siding onto the main track.

From the construction and arrangement of parts as above set forth, it will be seen that when the switch shall have been opened o manually it will be automatically closed by the action of the train in leaving the switch. The necessity of the switchman returning to the switch after a train has passed in order to close it, is not only obviated, but the closing of the switch is rendered certain, there being no occasion for relying upon the memory of any one to close it.

A switch or signal stand F of any preferred form will preferably be provided and will be o operated through the medium of a suitable rod F, connected at one end to the operating mechanism of said switch-stand and at the other end to the rod f.

Various slight changes might be made in 5 the details of construction of my invention without departing from the spirit thereof or limiting its scope, and hence I do not wish to limit myself to the precise details of construction herein set forth; but,

o Having fully described my invention, what I claim as new, and desire to secure by Letters Patent, is—

1. The combination with a main track, siding, pivoted switch rails, and means for shifting these pivoted switch rails, of latch mechanism adapted to release this shifting mechanism to allow the pivoted switch rails to resume their normal position, a sliding bar connected with the latch mechanism, and in position to receive a wheel flange between it and one of the rails whereby to be operated by the passing car or train to release the latch mechanism, and a movable bar or rail in position to be controlled by the passing car and arranged to permit the pivoted switch rails to move when the car passes from it, substantially as set forth.

2. The combination with a main track, siding, pivoted switch rails, and operating mechanism for shifting these pivoted switch rails, of latch mechanism adapted to release the shifting mechanism to throw the pivoted switch rails back to their normal position, a spring bar having loose connection with the latch mechanism, said bar adapted to be operated by a passing car whereby to release the latch, and a movable bar or rail in position to be controlled by the passing car and arranged to permit the pivoted switch rails to move when the car passes from it, substantially as set forth.

3. The combination with the pivoted switch rails of a railroad switch, of an operating lever for shifting said switch rails to open the switch, devices for automatically closing the

switch after a train shall have passed, an operating lever for setting said closing devices, said operating levers being so disposed that when in their normal positions with the switch closed, one lever will be over the other, 70 and a lock for locking the top lever in its normal closed position, substantially as set forth.

4. The combination with the pivoted rails of a railroad switch and a movable bar adjacent to one of the track rails, of a lever connected with the switch rails and movable bar whereby to shift the same, devices for automatically closing the switch, a lock for retaining said devices set after the switch shall 80 have been opened, a spring bar adjacent to one of the track rails adapted to be moved by the flange of a wheel, and a connection between said spring bar and lock whereby to primarily release the closing mechanism so as 85 to permit it to operate to close the switch when the last wheel of the train shall have passed over the said movable bar, substantially as set forth.

5. The combination with the pivoted rails 90 of a railroad switch and a movable bar located adjacent to one of the track rails, said movable bar having curved slots therein, a series of brackets for retaining said movable bar in proper position and pins passing through said 95 brackets, slots and the track rail, of a lever connected with said movable bar and pivoted switch rails, means connected with said lever for automatically closing the switch, means for primarily locking said closing devices and 100 a spring bar adjacent to one of the track rails and adapted to be operated by the flange of a wheel to primarily release the closing devices so as to permit the latter to operate to automatically close the switch when the last 105 wheel of the train shall have passed over the said movable bar, substantially as set forth.

6. The combination with the pivoted rails of a railroad switch, of an operating lever connected with said pivoted rails, a shaft, a 110 weighted arm at one end of said shaft, a depending arm at the other end of the shaft, a latch to engage the depending arm, a movable connection between said depending arm and said operating lever, a device to be operated 115 by the train for operating said latch to release the depending arm and means controlled by the train for permitting said weighted arm to drop and close the switch, substantially as set forth.

7. The combination with the pivoted rails of a railroad switch and a movable bar adjacent to one of the track rails, of a pivoted lever having three arms, a connection between one of said arms and the pivoted switch rails, 125 a connection between said lever and the movable bar, an operating lever, an arm adapted to move therewith, a connection between the last-mentioned arm and said pivoted lever, a slotted bar pivotally connected to the arm 130

which moves with the operating lever, a setting lever, an arm adapted to move with the setting lever and connected with said slotted bar, a shaft, a weighted arm at one end of the 5 shaft, a depending arm at the other end of the shaft, a connection between the depending arm and arm carried by the setting lever, a spring actuated latch bar to engage said depending arm, a spring bar located adjacent 10 to one of the track rails and adapted to be

moved by the flange of a wheel, and a connection between said spring bar and latch bar, substantially as set forth.

In testimony whereof I have signed this specification in the presence of two subscribing witnesses. 15
